UNITED STATES PATENT OFFICE.

EMIL KLAHN, OF WEEHAWKEN, NEW JERSEY.

GYROSCOPE.

1,192,532.

Specification of Letters Patent. Patented July 25, 1916.

Application filed July 15, 1912. Serial No. 709,367.

To all whom it may concern:

Be it known that I, EMIL KLAHN, a citizen of the United States, and a resident of Weehawken, in the county of Hudson and 5 State of New Jersey, have invented certain new and useful Improvements in Gyroscopes, of which the following is a specification.

The invention relates to gyroscopes; and 10 more particularly to the manner of supporting and driving the rotatable or gyroscopic member thereof.

It has for its object to simplify the mounting and driving of the said rotatable member without destroying the necessary freedom of oscillation of its axis of rotation; and, furthermore, to provide a force, other than the attraction of gravity, to act on such member.

20 A further object of the invention consists in so effecting the transmission of the gyroscopic property of the gyroscope member to another member or members, which it is desired the force should affect, that such transmitted force may be entirely suspended or 25 varied as desired, and also instantaneously applied thereto.

The nature of the invention will best be understood when described in connection 30 with the accompanying drawings, in which—

Figure 1 is a front elevation of the improved gyroscope. Fig. 2 is a plan thereof. Fig. 3 is a vertical section taken on the line 3—3, Fig. 2, but omitting the motor and 35 base.

Referring to the drawings, 10 designates any suitable base for an electric or other suitable motor 11, which is shown entirely incased. The driving shaft 12 of this driving member 11 projects beyond the top of the same; and about said shaft is mounted a magnetic member, as the suitably energized electro-magnet 13, which may be controlled by a switch 13' or the like. For driving, a disk 14 is preferably employed and is mounted over the shaft 12 near its outer end, a sleeve 15 thereof extending inwardly over the said driving shaft and within the core of electro-magnet 13, whereby said disk becomes strongly magnetized, as for the purpose hereinafter set forth.

The outer end of the shaft 12 is shown of reduced diameter, providing a shoulder 16. About this reduced portion is pivotally 50 mounted the rotatable gyroscopic member 17 and in such a manner as to have perfectly

free oscillation, limited, of course, but sufficient to allow it three degrees of freedom of rotation. Such universal joint between the gyroscopic member 17 and the shaft 12 may be effected in the following manner. As shown, a ball 18 is mounted about the reduced portion of the shaft 12, being held to the shaft by a screw 18', and abuts the shoulder 16. The ball is centrally fitted to the web of the member 17 by means of a lower plate 19, which is of magnetic material, and an upper plate or cap 20, both of which plates are suitably secured to the said web. The outer surface of plate 19 is arranged somewhat above the upper surface of the disk 14, leaving a slight air gap 21 between. The member 17 thus remains perfectly free to oscillate, and consequently a free oscillation of its axis of rotation is possible, the 75 said rotation of the member being accomplished through the action of disk 14 upon the plate 19. The magnetism of the disk 14 provides, furthermore, for a force, other than that due to gravity, to act upon the 80 member 17 whose gyroscopic property is, moreover, transmitted through this medium to the shaft 12 and from it to such parts as it is desirable that the force shall affect. The gyroscopic force may be regulated, or 85 even rendered entirely inoperative, by suitably controlling the excitation of magnet 13 by means of, for example, switch 13'. Upon closing the said switch, the gyroscopic property is instantaneously transmitted to the member or members it is desired that the 90 force should affect.

The manner herein set forth of effecting the connection between shaft 12 and member 17 to allow, within the hereinbefore mentioned limitation, perfect freedom of rotation of the latter affords a convenient construction, but I do not desire to be understood as restricting myself to such particular construction, for it is evident that the connection may be effected in other ways.

I claim:

1. A gyroscope, comprising a rotatable gyroscopic member, a driving member therefor upon which said member is mounted free to turn about one axis and free to make limited oscillations about two other axes, and means to rotate the gyroscopic member from the driving member without actual contact between the same.

2. A gyroscope, comprising a rotatable gyroscopic member, a driving member there-

for upon which said member is mounted free to turn about one axis and free to make limited oscillations about two other axes, and magnetic means to rotate the gyroscopic member from the driving member while maintaining the former's freedom of movement.

3. A gyroscope, comprising a rotatable gyroscopic member, a driving member therefor upon which said member is mounted free to turn about one axis and free to make limited oscillations about two other axes, magnetic means to rotate the gyroscopic member from the driving member while maintaining the former's freedom of movement and to transmit the gyroscopic property of the former to the latter, and means to control said magnetic means.

4. A gyroscope, comprising a rotatable gyroscopic member, a driving member therefor upon which said member is mounted free to turn about one axis and free to make limited oscillations about two other axes, and magnetic means carried by and rotating with said driving member to rotate the gyroscopic member while maintaining its freedom of movement.

5. A gyroscope, comprising a suitable driving member, and a shaft rotated there-

by; a gyroscopic member, and a universal joint connecting the same with said shaft; and magnetic means in operative relation to said shaft and in proximity to said gyroscopic member to rotate the latter and transmit its gyroscopic property to the said driving member.

6. A gyroscope, comprising a suitable driving member, and a shaft rotated thereby; a ball carried by said shaft; a gyroscopic member mounted upon said ball, and a magnetic plate carried by the gyroscopic member; and a magnetic member in operative relation to said shaft and in proximity to said magnetic plate.

7. A gyroscope, comprising a suitable driving member, and a shaft rotated thereby; a ball carried by said shaft; a gyroscopic member mounted upon said ball, and a magnetic plate carried by the gyroscopic member; and a magnetic disk carried by said shaft in proximity to said magnetic plate.

Signed at New York, in the county of New York and State of New York, this 13th day of July, A. D. 1912.

EMIL KLAHN.
